CLAIM

The ornamental design for a bag as shown and described.

DESCRIPTION

FIG. 1 is a front right perspective view of a bag showing our new design;

FIG. 2 is a front left perspective view of the design shown in FIG. 1;

FIG. 3 is a rear view of the design shown in FIG. 1;

FIG. 4 is front view of the design shown in FIG. 1;

FIG. 5 is a right side view of the design shown in FIG. 1;

FIG. 6 is a left side view of the design shown in FIG. 1;

FIG. 7 is a top view of the design shown in FIG. 1; and,

FIG. 8 is a bottom view of the design shown in FIG. 1.

FIGS. 1-8 include broken lines that are included for the purpose of illustrating portions of the bag that form no part of the claimed design. Colors form no part of the claimed design, and the gray tones do not represent any particular color.

1 Claim, 8 Drawing Sheets
